United States Patent

Des. 238,449

Patented Jan. 13, 1976

238,449

PAPER TOWELING

Ikki Matsumoto, Loveland, Ohio, assignor to The Procter & Gamble Company, Cincinnati, Ohio

Filed July 10, 1974, Ser. No. 487,360

Term of patent 14 years

Int. Cl. D5—03

U.S. Cl. D59—2 A

The single figure is a plan view of a paper toweling showing my new design.

I claim:

The ornamental design for a paper toweling, substantially as shown and described.
